Primary Examiner — Thomas Johannes(74) *Attorney, Agent, or Firm* — Abbey A. Lopez; Amy M. Foust(57) **CLAIM**

The ornamental design for a container for cleansing wipes, as shown and described.

DESCRIPTION

FIG. 1 is a perspective view of a container for cleansing wipes showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top elevational view thereof; and,

FIG. 7 is a bottom elevational view thereof.

The lightweight, dashed broken line portion of the figure drawings is included to show unclaimed subject matter only and forms no part of the claimed design.

The special dot-dash broken line in FIGS. 1, 2, 3, 4, 5, and 7 defines the bounds of the claimed design and, itself, forms no part of the claimed design.
